UNITED STATES PATENT OFFICE.

GEORGE L. ROBERTSON, OF PHILADELPHIA, PENNSYLVANIA, ASSIGNOR OF ONE-HALF
TO CHARLES MITCHELL, OF PHILADELPHIA, PENNSYLVANIA.

PNEUMATIC HAMMER.

1,071,263.

Specification of Letters Patent. Patented Aug. 26, 1913.

Application filed April 9, 1913. Serial No. 759,851.

To all whom it may concern:

Be it known that I, GEORGE LAWSON ROBERTSON, a citizen of the United States, residing at Philadelphia, in the county of Philadelphia and State of Pennsylvania, have invented certain new and useful Improvements in Pneumatic Hammers, of which the following is a specification.

My invention relates to improvements in pneumatic hammers, the object of the invention being to provide a movable head at the end of a fixed valve box, whereby compression of fluid in front of the head by the rearward reciprocation of the plunger causes said head to move, cushioning the plunger and opening inlet ports in direct communication with the space back of the plunger, whereby the initial forward movement of the plunger is accelerated.

20 A further object is to provide in a pneumatic hammer, an improved movable head which operates automatically being normally held in forward position by the pressure of fluid and momentarily moved rearwardly by the rearward reciprocation of the plunger.

With these and other objects in view, the invention consists in certain novel features of construction and combinations and arrangements of parts as will be more fully hereinafter described and pointed out in the claims.

In the accompanying drawings: Figure 1 is a fragmentary view in longitudinal section illustrating my improvements, showing the box head in normal forward position. Fig. 2 is a similar view showing the head in its rearward position. Fig. 3 is a view in cross section on the line 3—3 of Fig. 2, and Fig. 4 is a view in cross section on the line 4—4 of Fig. 2.

1 represents the barrel of a pneumatic hammer having a longitudinal bore 2 in which a plunger 3 snugly fits and is adapted to reciprocate. The barrel 1 at its rear end is enlarged in diameter and made hollow forming a cylindrical extension 4 in which a valve box 5 is mounted. The valve box 5 is held against rotary movement in the barrel by means of pins 6, and at its rear end has an annular flange 7 fitting against the end of the barrel. The hammer handle 8 is provided with a cylindrical cap 9 internally screw-threaded and engaging screw-threads on the cylindrical extension 4 of the

barrel. An internal annular shoulder 10 is provided in the cap which bears against the flange 7 securely binding this flange between said shoulder and the end of the cylindrical extension 4, so that longitudinal movement of the valve box is effectually prevented.

The cylindrical extension 4 has an annular series of ratchet teeth 11 in which a spring-pressed pin 12 engages to hold the parts against accidental movement. In the box 5, my improved valve 13 is mounted to reciprocate and has a longitudinal bore alining with the bore 2 of the barrel, and of the same diameter so that the plunger 3 fits snugly within the valve and reciprocates therethrough. The valve 13 is open at both ends, its movement in a forward direction being limited by a shoulder 14 in box 5, and the movement in the rearward direction limited by an internal annular flange 15.

The cylindrical central opening or bore of box 5 at its rear end is closed by a cylindrical block 16 forming an integral part of my improved movable box head 17 which is cylindrical in form, and has a leather disk cup 18 secured to a central lug 19 thereon by means of a washer 20 and a pin 21, and this cup 18 with the head 17 is adapted to reciprocate in a cylindrical casing 22. This casing 22 fits snugly within the fluid inlet chamber 23 at the rear end of the hammer provided within the cap 9, so that the head 17 is always open to communication with the live fluid pressure entering through inlet passage 24, and is normally pressed forwardly as indicated in Fig. 1.

The forward end of the block 16 forming an integral part of head 17 is reduced in diameter and snugly fits within the flange 15, and the rear end of valve 13, so as to form a cushioning head for an air pocket at the rear end of the valve. This block 16 has a central chamber 25 which communicates by radial ports 26 with an annular groove 27 around the block. This groove 27 is normally out of alinement with radial ports 28 between the end of casing 22 and valve box 5. These radial ports which may constitute a continuous chamber, communicate with longitudinal grooves 29 in the outer surface of casing 22, and I would have it understood that when I use this term "radial ports" for the passage 28, that the term is used in its broadest sense. Casing 110

22 is secured by screws 30 to the box 5, so that it is held against movement. The live fluid entering passage 24 when the parts are in the position shown in Fig. 1, passes 5 through the groove 29, radial ports 28, and relatively large longitudinal ducts 31 in box 5, and through openings 32 in valve 13, so as to drive the plunger forwardly.

The rearward movement of the plunger 10 after the openings 32 are closed by the plunger, will cause an air pocket or cushion between the plunger and the head, and the head will be moved rearwardly until the ports 26 register with the ports 28. Instantly, 15 the live fluid will flow through the ports 26 and chamber 25, and give the plunger its initial forward movement. The action therefore of the head operates to cushion the plunger and admit fluid back of 20 the plunger to accelerate its forward movement. The head will be instantly returned to its normal position by the pressure of live fluid behind the same, but the momentary rearward movement further compresses 25 the fluid and to that extent, increases the power thereof to drive the plunger forwardly.

My improved valve and arrangement of 30 ports and passages forms the subject matter of a separate application, Case F, executed on even date herewith, and I have in this application only referred to such parts as have bearing upon the particular invention in issue.

35 Various slight changes might be made in the general form and arrangement of parts described without departing from my invention, and hence I do not limit myself to the precise details set forth, but consider myself at liberty to make such changes and 40 alterations as fairly fall within the spirit and scope of the appended claims.

Having thus described my invention, what I claim as new and desire to secure by Letters Patent is:

1. In a pneumatic hammer, the combination with a barrel, a valve box fixed in the barrel, and having an opening therethrough, 50 a valve movable in said opening, of a movable head closing the rear end of the box, substantially as described.

2. In a pneumatic hammer, the combination with a barrel, a valve box fixed in the barrel, and having an opening therethrough, 55 a valve movable in said opening, of a movable head closing the rear end of the box, and said head having an integral block fitting within the rear end of the box, substantially as described.

3. In a pneumatic hammer, the combination with a barrel, a valve box fixed in the barrel, and having an opening therethrough, 60 a valve movable in said opening, of a movable head closing the rear end of the box, said head having an integral block fitting

within the rear end of the box, and a reduced end on said block adapted to fit within the valve, substantially as described.

4. In a pneumatic hammer, the combination with a barrel, a valve box fixed in the barrel, and having an opening therethrough, 70 a valve movable in said opening, of a movable head closing the rear end of the box, said head having fluid passages therein communicating with the valve, said passages normally closed, and opened by the rearward movement of the head due to the rearward movement of the hammer plunger, substantially as described.

5. In a pneumatic hammer, the combination with a barrel, a valve box fixed in the barrel, and having an opening therethrough, 80 a valve movable in said opening, of a movable head closing the rear end of the box, and said head having an integral block fitting within the rear end of the box, said head having fluid passages therein communicating with the valve, said passages normally closed, and opened by the rearward movement of the head due to the rearward 85 movement of the hammer plunger, substantially as described.

6. In a pneumatic hammer, the combination with a barrel, a valve box fixed in the barrel, and having an opening therethrough, 90 a valve movable in said opening, of a movable head closing the rear end of the box, said head having an integral block adapted to fit within the rear end of the box, a reduced end on said block fitting within the valve, said head having fluid passages there- 95 in communicating with the valve, said pas- sages normally closed, and opened by the rearward movement of the head due to the rearward movement of the hammer plunger, 100 substantially as described.

7. In a pneumatic hammer, the combination with a barrel, a valve box fixed in the barrel, and having an opening therethrough, 100 a valve movable in said opening, of a movable head closing the rear end of the box, and said head having an integral block fitting within the rear end of the box, said block having a central pocket, and radial ports communicating with said pocket and 110 connecting the same with an annular groove in the block, and said head moved by the rearward movement of the hammer plunger 115 into communication with live fluid powers, substantially as described.

8. In a pneumatic hammer, the combination with a barrel, a valve box fixed in the barrel, and having an opening therethrough, 120 a valve movable in said opening, of a movable head closing the rear end of the box, said head having an integral block fitting within the rear end of the box, a reduced end on said block adapted to fit within the valve, said block having a central pocket, and radial ports communicating with said 125 130

5 pocket and connecting the same with an annular groove in the block, and said head moved by the rearward movement of the hammer plunger into communication with live fluid ports, substantially as described.

9. In a pneumatic hammer, the combination with a barrel, a box secured within the barrel, a valve in the box, and a plunger mounted to reciprocate in the barrel and in 10 the valve, of a head closing the rear end of the box, a casing secured within the hammer and to the rear end of the box, a cup disk on the head movable in the casing, said casing open at its rear end to the live fluid, 15 said casing having longitudinal grooves in its outer face and radial ports at its inner end, and inlet ports in the head normally out of register with said last-mentioned ports, substantially as described.
10. In a pneumatic hammer, the combination with a barrel, a box secured within the barrel, a valve in the box, and a plunger mounted to reciprocate in the barrel, and in 20 the valve, of a head closing the rear end of the box, a casing secured within the hammer and to the rear end of the box, a cup disk on the head movable in the casing, said casing open at its rear end to the live fluid, said casing having longitudinal grooves in its 25 outer face and radial ports at its inner end, a block on the head fitting within the box and having a central chamber, said block having an annular groove, and radial ports connecting the annular groove with said 30 chamber, and said head normally pressed forwardly by the live fluid to position the last-mentioned groove out of register with the first-mentioned ports, and said head moved rearwardly by the rearward movement of the plunger to register the groove with said first-mentioned ports, substantially as described.

11. In a pneumatic hammer, the combination with a barrel having an enlarged cylindrical extension at its rear end, of a valve box fitting within the cylindrical extension and having an annular flange located against the end of said extension, a handle, an internally screw-threaded cap on the 45 handle screwed onto the casing, said cap having an internal shoulder engaging the flange and binding the same against the extension, a cylindrical casing secured to the valve box and fitting within the cap, and a 50 movable box head closing the rear end of the valve box and fitting snugly within the casing, substantially as described.

12. In a pneumatic hammer, the combination with a barrel having an enlarged cylindrical extension at its rear end, of a valve box fitting within the cylindrical extension

and having an annular flange located against the end of said extension, a handle, an internally screw-threaded cap on the handle screwed onto the casing, said cap having an 65 internal shoulder engaging the flange and binding the same against the extension, a cylindrical casing secured to the valve box and fitting within the cap, a movable box head closing the rear end of the valve box, 70 and fitting snugly within the casing, said head having an integral central block projecting into the rear end of the valve box, substantially as described.

13. In a pneumatic hammer, the combination with a barrel having an enlarged cylindrical extension at its rear end, of a valve box fitting within the cylindrical extension and having an annular flange located against the end of said extension, a handle, 75 an internally screw-threaded cap on the handle screwed onto the casing, said cap having an internal shoulder engaging the flange and binding the same against the extension, a cylindrical casing secured to the 80 valve box and fitting within the cap, a movable box head closing the rear end of the valve box and fitting snugly within the casing, said head having an integral central block projecting into the rear end of the 85 valve box, an internal annular flange in the box, a movable valve in the box limited in its rearward movement by said flange, and said block having an extension projecting through the flange and into the valve, 90 substantially as described.

14. In a pneumatic hammer, the combination with a barrel having an enlarged cylindrical extension at its rear end, of a valve box fitting within the cylindrical extension 100 and having an annular flange located against the end of said extension, a handle, an internally screw-threaded cap on the handle screwed onto the casing, said cap having an internal shoulder engaging the 105 flange and binding the same against the extension, a cylindrical casing secured to the valve box and fitting within the cap, a movable box head closing the rear end of the valve box and fitting snugly within the casing, 110 said block and said casing having inlet ports registering only when the head is moved rearwardly by the action of the plunger within the barrel, substantially as described.
